UNITED STATES PATENT OFFICE.

DANIEL B. LUTEN, OF INDIANAPOLIS, INDIANA.

RETAINING-WALL TIE.

1,278,364.

Specification of Letters Patent. Patented Sept. 10, 1918.

Application filed July 27, 1918. Serial No. 247,036.

To all whom it may concern:

Be it known that I, DANIEL B. LUTEN, a citizen of the United States, residing at Indianapolis, in the county of Marion and State of Indiana, have invented a new and useful Retaining-Wall Tie, of which the following is a specification.

It is the object of my invention to provide a protected reinforcing anchorage for a fill-retaining wall; and especially to provide a protected cross connection between two walls which hold a fill between them, such as the two side walls of a bridge.

It has heretofore been proposed to connect the spandrel or other side walls of a bridge by tension rods extending through the fill, and to embed such tension rods in concrete to protect them. In practice, however, this has been found to be open to serious objection, because of the distortion of the tension rods by the settlement of the fill, which distortion has not only increased the strain on the tension rods but has caused cracking of the protecting embedding concrete and has thereby admitted water which has corroded the tension rods and caused them to break and thereby to allow the walls to fail.

In order to prevent this distortion, it has been proposed to make the embedding concrete for these tension rods sufficiently massive so that it forms a beam which resists flexure. This is also open to objection. If the beam thus formed is so located that the tension rods are in the bottom thereof, the bending of the beam, though slight, induces greater tension in the tension rods, and thereby requires more tension rods to be provided. On the other hand, if the beam is so located that the tension rods are in the top thereof, not only must additional tension rods be provided in the bottom of such beam in order to resist the bending thereof, but in addition compression stresses are set up in the top thereof in opposition to the tension in the rods embedded in such top, and as tension actually exists in these top rods the stresses in the top of the beam are reversed from compression to tension and additional stresses are thrown on the additional rods which are embedded in the bottom of the beam; thus either requiring an unduly large number of tension rods in the bottom of the beam or else resulting in a breaking of the bottom tension rods and a failure of the beam. In addition, the beam

(of either kind) does not settle with the fill, so that upon such settlement a cross ridge appears in the paving above such beam; such ridges also frequently appear over the tension rods even though they are not in beams and are simply embedded in the fill.

By my present invention I provide a solution which is free from these objections; which gives between the side walls—or between any fill-retaining wall and an anchorage, whether or not the anchorage be another wall—a tension connection requiring a minimum amount of reinforcements; which entirely avoids the bending stresses on the tension rods and gives such rods efficient protection against corrosion; and which avoids the formation of any cross ridges in the paving.

The accompanying drawing illustrates my invention. Figure 1 is a partial longitudinal section through an arch bridge in which the spandrel walls are interconnected in accordance with my invention, being taken substantially on the line 1—1 of Fig 2; and Fig. 2 is a transverse section through such bridge, taken substantially on the line 2—2 of Fig. 1.

I have shown my invention in connection with an arch bridge; though it is obviously not limited to that type of bridge, or, indeed, to any type of bridge, for it applies to any two walls with a fill between them, and even to a single fill-retaining wall. In this bridge as shown there is the arch 10 on the axial ends of which are the upstanding spandrel walls 11 surmounted by railings 12. The arch carries the usual fill 13 between the spandrel walls 11, which are side walls to retain such fill; and on top of the fill may be any usual paving 14.

The spandrel walls 11 are interconnected by tension rods 15 which extend from one spandrel wall to the other. These tension rods are preferably embedded in a coating 16 of concrete; though any other protective coating may be used, or a protective coating may be omitted. In order to protect the tension rods 15 and their protective coatings 16 (if any) from bending stresses, I provide separate load-carrying members 17 over them but spaced from them, which load-carrying members extend from one spandrel wall to the other. I prefer to make these load-carrying members 17 arch-shaped, as is clear from Fig. 1, and to make them all

concrete; but their shape and the material of which they are made may be varied. The load-carrying members 17 support the load of the fill above them; but because they are spaced from the tension rods 15 with their respective coatings 16 they do not transmit this load to such tension rods, and thus keep the tension rods free from bending stresses.

In erecting the structure, I build the arch 10 with its spandrels and railing in the usual manner, and provide the interconnecting tension rods 15 between the spandrels. Then as the fill is put in to the level of each tension rod, I leave a trough in the fill beneath such tension rod, and fill the trough 15 and cover the rod with concrete, to protect the rod. Then I place the load-supporting member 17 over the rod 15 and its protecting coating. I may construct this load-supporting member in place, or may build it separately and put it bodily into its position. In either case, it rests on the fill at the sides of the tension rod, and is spaced from the tension rod and its protecting 20 coating to leave a free space 18. Then I complete the fill in the usual manner, covering the load-supporting member 17.

By this construction, the tension rods 15 and their protecting coatings 16 are efficiently guarded against bending stresses from the superadjacent fill, so that there is no tendency to bend them and thus no tendency to crack the protecting coatings 16. This results in efficient protection 30 against corrosion of the tension rods. In addition, as the tension rods 15 have no other stresses than the tension stresses produced by the tendency to push apart the spandrel walls 11, they may be made of 35 minimum size and number. Moreover, as the members 17 settle with the fill, no cross ridges appear in the paving 14.

I claim as my invention:

1. In combination with an arch and spandrel walls and a fill on the arch between the spandrel walls, of a tension member interconnecting the spandrel walls through the fill, and a load-carrying member over the tension member and spaced therefrom to keep the weight of the fill off the tension member.

2. In combination with an arch and spandrel walls and a fill on the arch between the spandrel walls, of a tension rod embedded 55 in concrete and interconnecting the spandrel walls through the fill, and a load-carrying member over said tension rod and its embedding concrete and spaced therefrom to keep the load of the fill off said tension rod and its embedding concrete.

3. In combination with an arch and span-

drel walls and a fill on the arch between the spandrel walls, of a tension member interconnecting the spandrel walls through the fill, and an arch over said tension member and spaced therefrom and extending from one spandrel wall to the other through the fill to take the load of the superjacent fill and keep it off said tension member.

4. In combination with two walls with a fill between them, of a tension member interconnecting the two walls through the fill, and a load-carrying member over the tension member and spaced therefrom to keep the weight of the fill off the tension member.

5. In combination with two walls with a fill between them, of a tension rod embedded in concrete and interconnecting the two walls through the fill, and a load-carrying member over said tension rod and its embedding concrete and spaced therefrom to keep the load of the fill off said tension rod and its embedding concrete.

6. In combination with two walls with a fill between them, of a tension member interconnecting the two walls through the fill, and an arch over said tension member and spaced therefrom and extending from one wall to the other through the fill to take the load of the superjacent fill and keep it off said tension member.

7. In combination with a fill-retaining wall with its fill behind it, of a tension rod connected to said wall and extending therefrom into the fill to an anchorage, and a load-carrying member over the tension member and spaced therefrom to keep the weight of the fill off the tension member.

8. In combination with a fill-retaining wall with its fill behind it, of a tension rod embedded in concrete and extending from said fill-retaining wall into the fill to an anchorage, and a load-carrying member over said tension rod and its embedding concrete and spaced therefrom to keep the load of the fill off said tension rod and its embedding concrete.

9. In combination with a fill-retaining wall with its fill behind it, of a tension rod connected to said wall and extending therefrom into the fill to an anchorage, and an arch over said tension member and spaced therefrom and extending from said fill-retaining wall to said anchorage through the fill to take the load of the superjacent fill and keep it off said tension member.

In witness whereof I have hereunto set my hand at Indianapolis, Indiana, this 24th day of July, A. D. one thousand nine hundred and eighteen.

DANIEL B. LUTEN.
